Feschemacher & Stearns.

United States Patent Office.

LEVI HEYWOOD, OF GARDNER, MASSACHUSETTS.

Letters Patent No. 74,913, dated February 25, 1868.

IMPROVEMENT IN RATTAN-MACHINES.

The Schedule referred to in these Letters Patent and making part of the same.

TO ALL WHOM IT MAY CONCERN:

Be it known that I, LEVI HEYWOOD, of Gardner, in the county of Worcester, and State of Massachusetts, have invented certain Improvements in Machines for Splitting Rattan, of which the following is a full, clear, and exact description, reference being had to the accompanying drawings, making part of the specification, in which—

Figure 1 is a perspective view of my improvements.

Figure 2 is a longitudinal section through the centre of the same.

Figure 3 is a transverse section on the line xx of fig. 2.

Figure 4 is a modification to be referred to.

In machines for splitting rattan it is very important that the central tube or "quill," which separates the pith from the exterior shell of the rattan, should be more or less in advance of the cutters, according to the different degrees of hardness of the rattan to be split, in order that the cutters may not injure the strength of the fibre or fracture the strands as they are separated.

My invention relates particularly to certain improvements in machines for splitting rattan for which I have an application for Letters Patent of the United States now pending, and the object of my present invention is to simplify the construction by dispensing with the cutter-block, and consists in a central tube or "quill," provided with slots for receiving the several cutters to be adjusted.

To enable others skilled in the art to understand and use my invention, I will proceed to describe the manner in which I have carried it out.

In the said drawings, A represents a hollow circular "quill" or tubular cutter, the front, a , of which is carefully brought to a sharp edge to allow it to separate the pith from the hard exterior or enamelled shell of the rattan, the "quill" being made hollow to allow the pith to pass out of the machine. From a to a point, b , some distance back, the tube is of the same diameter, in order that it may readily be sharpened when worn away by use. From b to c the tube gradually curves upward, and the portion of its exterior surface from c to d represents a frustum of a pyramid, the diameter at d being slightly greater than at c , an enlargement, 5, being thus made in the tube, which is cut out from d to b , forming slots for the reception of cutters B, which split the enamelled exterior of the rattan, after being separated from the pith by the central tube or "quill," the depth of each slot at its rear end, d , extending to nearly the surface of the tube from d to f , which is of a cylindrical form, and of a slightly larger diameter than the front portion of the tube from a to b , by which construction the cutters B may be readily moved back and forth to bring their knife-edges, g , more or less behind the front edge a , and, when nicely adjusted, are secured in place by screws C, which are turned down so as to bring them against the outer surface of the cutters.

It will thus be seen that the adjustments of the cutters, with respect to their distance from the edge of the "quill," may be performed in an extremely convenient and expeditious manner; and should the cutters require sharpening it is simply necessary to remove them by unclamping the screw C, when the tube is also in a position free to be sharpened. The tube or "quill" may be of uniform diameter throughout its length, (see fig. 4,) and be provided with a screw-thread, i , to fit a corresponding screw-thread in the interior of the enlargement 5, by which means the tube may be screwed more or less in advance of the cutters, and I am enabled to sharpen a greater portion of its length.

Claim.

What I claim as my invention, and desire to secure by Letters Patent, is—

A central tube or "quill," provided with slots or openings, in combination with a series of adjustable cutters B, substantially as and for the purpose set forth.

LEVI HEYWOOD.
